CLAIM

The ornamental design for a produce bag dispenser, as shown and described.

DESCRIPTION

FIG. 1 is a top, front, and right side perspective view of a produce bag dispenser with a roll of produce bags operatively mounted thereon;

FIG. 2 is a top, front, and right side perspective view of the produce bag dispenser of FIG. 1 with the roll of produce bags removed;

FIG. 3 is a front view thereof;

FIG. 4 is a right side view thereof;

FIG. 5 is a top view thereof;

FIG. 6 is a rear view thereof;

FIG. 7 is a left side view thereof; and,

FIG. 8 is bottom view thereof.

The broken lines shown in a dash-dash pattern depict portions of the article and environmental structure that form no part of the claimed design.

1 Claim, 8 Drawing Sheets
